UNITED STATES PATENT OFFICE.

WILLIAM O. BACKES, OF INDEPENDENCE, KANSAS.

WIRE-REEL.

No. 884,974.

Specification of Letters Patent. Patented April 14, 1908.

Application filed July 31, 1907. Serial No. 386,386.

To all whom it may concern:

Be it known that I, WILLIAM O. BACKES, a citizen of the United States, residing at Independence, in the county of Montgomery, 5 State of Kansas, have invented certain new and useful Improvements in Wire-Reels; and I do hereby declare the following to be a full, clear, and exact description of the invention, such as will enable others

10 skilled in the art to which it appertains to make and use the same.

This invention relates to machines for stringing and re-winding wire and more particularly to that class which are supported on 15 a wagon body and are used for the purpose of taking up or unwinding fence wire, the wagon being driven along as the fence is put up or taken down, and the wire being wound or unwound, as the case may be. It is noticeable in the present device of this class that the reel upon which the wire is wound is of such length as to extend almost entirely across the wagon body and the crank handle by means of which the reel shaft is to be rotated is consequently located to one side of the 20 wagon body. This arrangement is very undesirable for the reason that the operator must reach out in order to grasp the crank handle and he is frequently in the way of the 25 wire being wound or unwound. For this reason I have provided a device of this character of such construction that it is unnecessary for the operator to reach out for the handle, it being located at the middle of the 30 wagon body and the reel upon which the wire is wound is located to one side of the handle and extends across the other half of the wagon body. I have furthermore provided means whereby the shaft may be 35 40 45

swung to permit the ready engagement thereon of a new or empty reel in case the machine is being used in winding up wire from a fence being taken down and for the engagement thereon of a full reel under other conditions.

In the accompanying drawings, Figure 1 is a rear elevation of a wagon showing the application of my invention, Fig. 2 is a top plan view of the wagon bed and the machine, Fig. 50 55 60 65 70 75 80 85 90 95 100 105 110

3 is a side elevation, and, Fig. 4 is a detail perspective view of the upper end of the machine frame showing the construction of the reel shaft bearings.

In the drawings 5 denotes the side boards 55 of a wagon box and 6 the bed thereof.

The machine embodied in my invention

comprises a frame including a pair of vertically extending uprights one of which is indicated by the numeral 7, and the other by the numeral 8, the upright 7 being secured to the right side board of the wagon body and the upright 8 to the left side board. The upright 7 is of considerably less height than the upright 8 for a purpose which will presently be made apparent.

The upright 8 is braced in the position stated by means of an upright brace 9, to which it is bolted, the said brace being secured to the inner face of the side board at the corresponding side of the wagon body. 70 The upright 7 has its upper portion turned inwardly at right-angles, as at 10, thence upwardly, as at 11, and secured by means of bolts to the lower end of the portion 11 of the frame are the upper ends of braces 12 and 13 75 the former being extended forwardly and secured to the bed 6 and the latter rearwardly and also secured to the bed.

The upper end of the portion 11 of the frame, is of yoke formation, as indicated at 13, and mounted in the yoke for rocking movement is a bearing 14 in which is journaled a shaft 15, the other end of the shaft being received in a similar yoke 16 formed at the upper end of the upright 8. In order 80 that the last-mentioned end of the shaft may be normally held securely in its bearing, a cap plate 17, is swiveled as at 18 to the upper end of one arm of the yoke 16 and adjacent its opposite end the plate is provided 85 with a slot for the reception of a threaded stud 20, formed at the other arm of the yoke, there being a nut 21 engaged upon the stud. Intermediate the two bearings, the shaft is squared as indicated at 22, and a wire reel 23 90 is engaged removably upon this portion of the shaft it being understood that in order to place the reel upon the shaft it is only necessary to loosen the nut 21 and swing the cap plate around so that the shaft may be swung 95 vertically with its bearing 14. It will also be seen from the drawings and the foregoing description of my invention that the crank handle by which the shaft is to be rotated is readily accessible at all times the said crank 100 shaft being indicated by the numeral 24 and being fixed upon the inner end of the shaft.

What is claimed is,

The combination with a wagon body, of an upright secured to one side of the body and 110 extending upwardly therebeyond, an upright secured to the other side of the body

and bent at right angles to extend inwardly and thence bent upwardly in a vertical plane, the upper end of the last-mentioned portion and the upper end of the first-mentioned upright being of yoke formation, a bearing mounted for rocking movement in the yoke upon the said upwardly-extending portion of the last-mentioned upright, a shaft journaled in the bearing and adapted to be rocked therewith, the other end of the shaft being journaled in the yoke at the upper end of the first-mentioned upright, a cap plate

swiveled to the upper end of one of the arms of the last-mentioned yoke, means for holding the cap plate in a position to close the yoke and retain the shaft therewithin, and a crank handle secured at the inner end of the shaft.

In testimony whereof, I affix my signature, in presence of two witnesses.

WILLIAM O. BACKES.
